(57) **CLAIM**

The ornamental design for a switch, as shown and described.

DESCRIPTION

FIG. 1 is a front view of the switch of the present invention, showing our new design;

FIG. 2 is a back view thereof;

FIG. 3 is a top view thereof;

FIG. 4 is a right side view thereof;

FIG. 5 is a left side view thereof;

FIG. 6 is a bottom view thereof;

FIG. 7 is a first view thereof, as seen from the front, bottom and right side;

FIG. 8 is a second view thereof, as seen from the top, back and left side; and,

FIG. 9 is a cross-sectional view thereof taken along the line 9—9 in FIG. 1.

The broken lines showing portions of the switch is for illustrative purposes only and forms no part of the claimed design.
